UNITED STATES PATENT OFFICE.

HENRY NOEL POTTER, OF PITTSBURG, PENNSYLVANIA, ASSIGNOR TO
GEORGE WESTINGHOUSE, OF PITTSBURG, PENNSYLVANIA.

ELECTRIC LAMP.

SPECIFICATION forming part of Letters Patent No. 730,216, dated June 2, 1903.

Application filed April 27, 1900. Serial No. 14,600. (No model.)

To all whom it may concern:

Be it known that I, HENRY NOEL POTTER, a citizen of the United States, residing at Pittsburgh, in the county of Allegheny and State of Pennsylvania, have invented a new and useful Improvement in Electric Lamps, of which the following is a specification.

My invention relates to electric lamps of the type in which the light-emitting body is a non-conductor when cold and becomes an efficient conductor when its temperature is sufficiently raised by independently-generated heat.

The object of my invention is to provide a lamp of the type indicated which shall be simple, compact, and inexpensive in construction and durable and efficient in operation and one in which the operative relation of the several parts shall be independent of the position of the lamp as a whole—that is to say, one in which the lamp will operate efficiently and satisfactorily when the axis of the lamp is in either a vertical or horizontal position or disposed at any angle between the two.

With these ends in view I have devised the means shown in the accompanying drawings, in which—

Figure 1 is a view partially in section and partially in side elevation of a lamp constructed in accordance with my invention. Fig. 1^a is a plan view of the heater and the connecting device between the same and the inner-glower-terminal. Fig. 2 is a view similar to Fig. 1 except that the housing and globe for the lamp are omitted and the parts are shown at right angles to the position indicated in Fig. 1. Fig. 3 is a detail side elevation corresponding to the lower portion of Fig. 2, but illustrating a modified form of return-conductor for the glower and heater. Fig. 4 is a plan view of the supporting-plate for the heater and glower. Fig. 5 is a detail sectional view of one of the devices for making separable circuit connections between terminals upon the removable element of the lamp and terminals upon the permanent portion of the lamp. Fig. 6 is a diagram of the lamp-circuits. Fig. 7 is a diagram of a modified arrangement of lamp-circuits. Fig. 8 is a view, partially in side elevation and par-

tially in section, of a lamp of modified construction. Fig. 9 is a sectional view of a modified construction of cut-out device, the electrical conductors being indicated diagrammatically. Fig. 10 is an enlarged view, in front elevation, of the combined ballast and cut-out mechanism.

Referring to Figs. 1 to 6 of the drawings, the glower 1 is connected by the terminal wire 2 at its outer end to the outer end of a supporting return-conductor 3. This conductor 3 is of zigzag form in order that the casting of dense shadows upon the globe may be avoided.

The return-conductor may be made to assume different forms from that here shown, provided it is so constructed and located with reference to the glower that the umbra shall be located adjacent to said conductor instead of being cast upon the globe. As one modification I have shown in Fig. 3 a supporting and returning conductor 3^a of helical form which surrounds the glower.

The terminal wire 4 at the inner end of the glower passes loosely through the tubular portion of a guide-bushing 5 and is fastened to one end of a terminal plug or pin 6, this pin being seated in a tubular screw 7, that is centrally located in a skeleton or open-work plate 8. This plate 8 is also provided with three tubular screws 9, 10, and 11, adjacent to its edges and suitably disposed to accommodate the terminal rods, which will be hereinafter described. The heater 12 for the glower is of spiral or helical form, symmetrically disposed around the glower, and preferably consists of a helix of insulating material, around which is coiled a fine platinum wire which constitutes the heating-conductor. The outer terminal 13 of the heater-wire is either joined directly to the outer end of the conductor 3 or to the glower terminal wire 2. A small rod 14 is fastened to the outer end of the heater to serve as an additional support for maintaining the outer ends of the glower and heater in proper relative position. The inner end of the supporting-body of the heater is attached to a projection 15 on the insulating and supporting piece 5, so as to maintain the tubular portion substantially in alignment with the heater-axis. The glower

is thus retained in proper relation to the heater, and at the same time the connection is such as to permit of a free longitudinal expansion and contraction of the heater and glower independently of each other. The inner terminal wire 13^a of the heater is fastened to the outer end of a wire 16, the inner end of which projects through the supporting-plate 8 and is fastened to the terminal screw 9, preferably by coiling it about said screw and beneath the nut 9^a. This nut being of hexagonal form, the end of the wire 16 may be bent upward against the side of the nut, and thus serve to lock it in the position as is indicated in Figs. 1 to 4. The inner end of the return-conductor 3 projects through the plate 8 and is similarly bent around the tubular screw 11 and clamped in position by the nut 11^a, the free end of the conductor being bent upward against the side of the nut to lock it in position in the manner already described with reference to the wire 16 and nut 9^a. The tubular screw 7 is electrically connected to the screw 10 by means of a wire 17, that is embedded in the plate 8 and the ends of which are coiled around the respective screws 7 and 10 and bent upward against the sides of the clamping-nuts 7^a and 10^a in the manner already described with reference to the other conducting-wires and nuts that are supported by the plate 8. It will be observed that all portions of the plate 8 not actually needed for supporting the terminal devices are cut away, so as to form an open-work structure, and thus permit of the free passage of air to assist in conducting away the heat, and thus maintain a comparatively low temperature in the lamp.

The globe 18, that surrounds the glower and heater, is supported by a housing 19, having ventilating-openings 19^a and to the lower edge of which it is attached by means of one or more locking-screws 20. Projecting upward from each of the tubular screws 9, 10, and 11 is a pin 21, which may be formed of the same material as the screw and constitute an integral part of it, if desired; but I find it convenient and desirable to form the screws of brass and the pins of a metal, such as aluminium, that is soft and the surface of which does not oxidize objectionably. I prefer, therefore, to make the screws 7, 9, 10, and 11 of the same form and material and provide each of them, except the screw 7, 55 with a pin 21, that is permanently and rigidly seated in the screw and projects upwardly therefrom, as indicated.

The external circuit connections of the lamp are shown as made by means of the head of a screw 22 at the end of the lamp structure opposite the globe 18 and by a band 23, (shown as of screw-threaded form,) adapted to fit the well-known form of Edison incandescent-lamp socket. These parts 22 and 23 are supported by a tubular body 24, of suitable non-conducting material, such as porcelain, which is seated in the upper end of the housing 19.

In the upper end of the tubular body 24, is seated a small magnet-coil 25, the core 26 of which is engaged by the screw 22, so as to fasten the coil and core in position in the lamp. The inner end of the core 26 is seated in a pocket or depression 27 in the end of an air-tight chamber 28 and may be cemented thereto. The chamber 28 is preferably a glass tube from which the air is exhausted and which contains a body of inert gas, such as hydrogen. The connection between the core 26 and the tube 28 is such that the latter will be supported by the former when the parts are assembled in the proper relative position. Within the tube 28 are contained the ballast resistance-wire 29, the supporting wire frame 30 therefor, and the circuit making and breaking devices for the heater-circuit, all of the said parts being supported by the inwardly-projecting portion 27 of the tube 28, in which the core 26 is seated. The movable member of the circuit making and breaking devices is shown in the form of a rod or tube 31, formed in whole or in part of magnetizable material and pivoted at approximately its middle point upon a portion 32 of a wire 33, one end of which is rigidly connected to the inwardly-projecting portion 27 of the tube 28. The part 32 of the wire is preferably disposed at right angles to the axis of the lamp, and from the free end of this portion, the wire projects downwardly nearly to the lower end of the support 30 for the ballast-wire 29 and from that point is bent backward upon itself to the lower end of the pivoted rod 31. From this point the wire projects across the lower end of the rod 31 at 33^a, then parallel thereto at 33^b, and then at right angles thereto at 33^c. The parts 33^a and 33^b have curved seats to receive the rod 31, and the spring action of the wire 33 is such that the pressure of the part 33^c just below the part 32 will serve to hold the outer end of the rod 31 away from the core 26. When in this position, the outer end of the device 31 rests against a terminal piece 34, one end of which is rigidly supported by the inwardly-projecting portion 27 of the tube 28. When the magnet 25 is energized, the part 31 will be rocked on its pivot so as to move its outer end away from the contact-piece 34 and its outer end into engagement with the seat formed in the part 33^c, this spring-buffer being provided in order to prevent any rattling of rod 31 against part 27 when alternating current is employed in the operation of the lamp.

In order to make suitable circuit connections between the controlling devices contained in the tube 28 and the glower and heater and between the magnet-coil 25 and the glower and heater, I provide three terminal rods 35, and since these are preferably made of aluminium, which is not readily soldered, I form each rod of two strips of metal 36 and 37, the strip 36 being bent at its lower end to form a tube 36^a of the proper size to receive the corresponding pin 21 and make a close fit therewith. The strip 36 is also pro-

vided with a slit 36^a at a suitable point above the tubular portion 36^a, and the other strip, 37, is provided with a tongue 38, that projects through the slit 37 and is bent down against 5 the strip 36 on the opposite side, this connection serving to hold the parts in proper position with their contiguous faces in close contact. At a suitable point above the slit and tongue connection I bend the strips 36 and 10 37 apart sufficiently to form a tubular socket 39, adapted to receive a terminal pin 40. The two strips 36 and 37 may be separate pieces clamped together and to the inner portion 15 of the insulating body 24 by means of screws or rivets, or they may be parts of a single strip that is doubled back upon itself, as indicated in Fig. 1.

The circuits other than those already described are made as follows: The terminal 20 wire 41 from the coil 25 is fastened to a plug 40, which may be of aluminium or other suitable soft metal, and this plug is removably seated in the socket 39 of the terminal rod 35, with which the pin 21, projecting from the 25 screw 10, engages. The other terminal wire, 42, of the magnet 25 leads into the tube 28, and its inner end is fastened to one end of the ballast-wire 29. The terminal wire 43, the outer end of which is soldered to the shell 23, has 30 its inner end fastened to a terminal plug 40, like that already described, and this plug is removably seated in the socket 39 of the terminal rod 35, that is connected to the return-conductor 3. Instead of employing the plug 35 40 the end of the wire 43 may be soldered to the rod 35, if desired. The terminal piece 34 is connected by means of a wire 44 to a plug 40, that is removably seated in the socket 39 in the terminal rod 35, corresponding to the 40 heater terminal wire 16, the wire 44 being sealed in the wall of the tube 28, as is also the wire 42.

It will be seen from the foregoing description, in connection with the illustration, that 45 the current coming into the lamp through the terminal screw 22 will pass through the magnet-core 26, the circuit-breaker member 31, the contact-terminal piece 34, and the corresponding connecting wires, plugs, and terminal rods 50 to the heater, and through the heater, the return-conductor 3, and connections to the shell 23 and out. As soon as the heat transmitted to the glower from the heater raises the glower to a conducting temperature the 55 current will pass from the magnet-core 26 through the ballast resistance, the coil of the magnet, the glower, the return-conductor 3, and connections to the shell. Thus the magnet will be energized and the lines of force 60 will act upon the pivoted circuit-breaker member 31 to rock it upon its pivot, thus breaking connection with the terminal piece 34, and therefore the circuit connections to the heater. This condition will be maintained 65 until the current is cut off from the lamp, when the parts will be automatically re-

turned to the positions indicated in the drawings.

It will be seen from the illustration and description that the relation of the heater and 70 glower is such that substantially the same amount of heat will be imparted to the glower and the same amount of light transmitted from the latter for all positions of the lamp, and consequently that the lamp is adapted 75 for use in connection with existing incandescent-lamp sockets, no matter what the position of such sockets may be. The electromagnetic cut-out is also so arranged that its action is independent of gravity, and its movable member is so held that it will not vibrate, and thus produce objectionable noise when the lamp is operated on alternating-current circuits.

In Fig. 7 of the drawings I have indicated 80 an arrangement of circuits which differs somewhat from that heretofore described. The several parts of the lamp, except as regards the circuit connections, are or may be the same as those already described, and 90 since the same reference-numerals are employed the description heretofore given may be read in connection with both this and the succeeding figures in so far as the same may be applicable. In the arrangement of circuits shown in Figs. 1 to 6 the current passing through the lamp does not traverse the cut-out coil 25 until the heater-circuit is broken. As shown in Fig. 7, the current 95 passing through the lamp traverses the cut-out coil 25^a at all times. Since the current passing through the heater is less than that taken by the glower, it is feasible to so proportion and adjust the parts of the circuit-breaker that the current flowing through the 100 lamp when the glower is not in circuit will be insufficient to move the armature of the cut-out, and thus break the heater-circuit. This arrangement of circuits is more sensitive than that previously described, since the 105 cut-out coil is energized at all times and the instant that the glower becomes conductive the extra current flowing will serve to break the heater-circuit.

In the lamp shown in Fig. 8 the parts included within the housing 19 may be the same as those shown in the preceding figures; but in this form of lamp I have shown a double globe 18^a, the space 18^b between the inner and outer walls of which is exhausted of air 110 in order that better lighting effects may be secured, such improved lighting effects being due to the substantial elimination of convection. In this form of lamp I have also shown a curved glower 1^a and a heater 12^a of zigzag 115 form that embraces but does not entirely surround the glower, the general axis of the heater being coincident with that of the glower. This form of heater I have shown in another application and have there designated it as a "wave-spiral." It will be understood 120 that there is no special co-operation 125

between this form of heater and glower and the vacuum-globe, and hence the forms of heater and glower shown in other figures may be here employed, or the forms may otherwise be varied as desired.

In Fig. 9 I have shown the circuits and some of the essential features of a lamp, the structure of which is the same as that shown in Figs. 1 to 6, except that the core 26^a of the 10 cut-out device is located inside the tube or chamber 28^a, the coil 25 being the only member of the cut-out structure that is located outside the chamber. It is not deemed advisable in any case to include the coil within 15 the chamber, for the reason that the air clings tenaciously to the coil surfaces and cavities, so that it is extremely difficult if not impossible to exhaust the chamber of air if the coil is included within it. Such air as would be 20 secreted by the coil if the latter were included in the chamber would subsequently be freed, so as to mix with the hydrogen and make moisture that would have a deleterious effect in the operation of the apparatus.

25 While I have shown and described specific details of construction, I desire it to be understood that said details may be varied within considerable limits without departing from the spirit and scope of my invention.

30 I claim as my invention—

1. An electric lamp of the type described, comprising a glower, a heater therefor, a ballast device, an automatic heater cut-out having a pivoted circuit making and breaking 35 member and a spring that bears against said member in each of its positions and thus prevents vibrations.

2. An electric lamp of the type described, comprising a glower, a heater therefor, a ballast device, a cut-out for the heater, the movable member of which is pivotally mounted, and a spring-arm, one end of which constitutes the pivot for said member and the other end of which bears against one end of said 45 member in all positions of the latter.

3. An electric lamp of the type described, comprising a glower, a heater therefor, a ballast device, an electromagnetically-actuated cut-out device for the heater and a spring-50 arm upon one end of which said device is pivoted and against the other end of which the device rests in each of its positions.

4. An electric lamp of the type described, comprising a glower, a heater surrounding 55 the same, a conducting-support for said glower and heater that is angularly disposed with reference to the glower, a ballast device, a cut-out for the heater and circuit connections.

60 5. In an electric lamp of the type described, a controlling device for the heater-circuit comprising a switch-arm formed in whole or in part of magnetizable material and pivotally supported at substantially its center of 65 gravity, a spring against which said switch-arm rests in each of its positions for prevent-

ing vibratory movement, and an electromagnet in inductive relation to said switch-arm.

6. An electric lamp of the type described, comprising a glower, a heater, a controlling device for the heater-circuit, a ballast for the glower-circuit, all of said parts being operatively independent of the position of the lamp, and the movable member of the circuit-controlling device being restrained against 75 vibration in every position that it assumes.

7. An electric lamp of the type described, having glower and heater terminal rods, each of which is formed of a strip of metal doubled upon itself and has an edge and an end 80 end socket for the reception of plug-terminals.

8. The combination with a glower of the type described, of a heating-conductor located adjacent to the glower and having different portions of its length disposed at different 85 angles to the glower-axis, a return-conductor located adjacent to the heater and having different portions of its length also disposed at different angles to the glower-axis and angularly disposed with reference to the corresponding 90 portions of the heating-conductor, and means for supporting the said parts.

9. The combination with a glower, a heating-conductor therefor and a return-conductor each of which has different portions of its 95 length disposed at different angles to the axis of the glower and to each other, the glower and the heating-conductor being supported by the return-conductor at one end, a non-conducting support for the other ends of said 100 devices, a ballast-conductor, a cut-out device, and a contact-terminal with which said other ends of the glower, the heating-conductor, and the return-conductor are respectively connected.

10. The combination with a glower of the type described, a spirally-arranged heating-conductor inclosing the glower and a metal-conductor adjacent to the heating-conductor and the glower and having different portions of its length disposed at different angles to the glower and to the corresponding portions of the heating-conductor, all united in a single terminal at one end, of insulated terminals for the other ends of said devices and a 115 supporting device having three terminals for the free terminals of the glower, the heating-conductor and the return-conductor.

11. The combination with a glower of the type described, of a heater having different portions of its length disposed at different angles to the glower-axis, a wire or rod adjacent to the heater having different portions of its length also disposed at different angles to the glower-axis and to the corresponding 120 portions of the heater and affording a return path for the currents transmitted through the heater, and a plate of insulating material carrying the glower, the heater and said wire or rod.

12. The combination with a glower of the type described, of a heater therefor, a zigzag

conductor located adjacent to the heater for protecting the same and affording a return path for the currents transmitted therethrough, an insulating plate, terminals carried

5 thereby for affording electrical connection with the terminals of the glower, the heater and the conductor upon one side, a terminal upon the opposite side, and a ballast-conductor making electrical connection with the last-named terminal.

13. The combination with a glower of the type described, of a heater rigidly connected to the glower at one end and loosely connected thereto at the other end whereby independent, longitudinal expansion and contraction are permitted.

14. In an electric lamp, the combination with a glower and heating-conductor, of a support therefor, a ballast-conductor, and an electric cut-out, an air-tight inclosing chamber for said ballast-conductor and cut-out, and detachable terminals for making electrical connections between the glower and ballast-conductor and the heater and cut-out, substantially as described.

15. In an electric-lamp structure, having a glower and heater, the combination with an electromagnetic cut-out or circuit-breaker, a ballast-conductor, an air-tight inclosing chamber for the ballast-conductor and the contact members of the circuit-breaker, of separable electric connections upon the outside of said chamber for affording electrical connections between the ballast-conductor and circuit-breaker and the glower and heater.

16. In an electric-lamp structure, a removable air-tight chamber having a ballast device and a circuit-interrupter contained therein.

17. In an electric-lamp structure, a removable air-tight chamber having a ballast device and a circuit-interrupter contained therein,

said circuit-interrupter being connected at one end with one end of the ballast device.

18. The combination with a glower of the type described, of a heater therefor and a ballast and circuit-breaker containing case located in alignment with the general axis of the glower and the heater.

19. The combination with a glower of the type described, of a heater therefor, a ballast and circuit-breaker containing case located in alignment with the general axis of the glower and the heater, and an inclosing globe surrounding said glower and heater.

20. In an electric lamp, a non-conducting plate having terminal screws seated therein, glower and heater terminal wires and binding-nuts for connecting said wires with said screws, the ends of the wires being bent upward against the sides of the nuts to lock them in position.

21. In an electric lamp of the type described, a spiral heater and a glower coinciding with the heater-axis and having one end rigidly connected to the corresponding end of the heater and having a loose connection between its other end and the corresponding end of the heater.

22. In an electric lamp of the type described, the combination with a glower and a heater rigidly connected together at one end, of a supporting-piece carried by the other end of the heater and having a guide-bushing for the glower terminal wire.

In testimony whereof I have hereunto subscribed my name this 25th day of April, A. D. 1900.

HENRY NOEL POTTER.
